UNITED STATES PATENT OFFICE

FRANCIS E. MASSELIN, OF PROVIDENCE, RHODE ISLAND, ASSIGNOR TO DOVERCRAFT COMPANY, INC., OF PROVIDENCE, RHODE ISLAND, A CORPORATION OF RHODE ISLAND

DESIGN FOR A CURTAIN SUPPORTING STRUCTURE

Application filed April 15, 1932. Serial No. 43,502. Term of patent 3½ years.

To all whom it may concern:

Be it known that I, FRANCIS E. MASSELIN, a citizen of the United States, residing at Providence, in the county of Providence and State of Rhode Island, have invented a new, original, and ornamental Design for Curtain Supporting Structure, of which the following is a specification, reference being had to the accompanying drawing, forming part thereof.

Fig. 1 is a front elevational view of a cur-

tain supporting structure showing my new design, and

Fig. 2 is a side elevational view of the same.

What I claim is:

The ornamental design for a curtain supporting structure, substantially as shown.

In testimony whereof I have affixed my signature.

FRANCIS E. MASSELIN.
